UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

Application filed May 14, 1921. Serial No. 469,665.

To all whom it may concern:

Be it known that I, PERLEY R. GLASS, a citizen of the United States, residing at Wayland, in the county of Middlesex and State of Massachusetts, have invented certain Improvements in Fastener-Setting Machines, of which the following description, in connection with the accompanying drawings, is a specification, like reference characters on the drawings indicating like parts in the several figures.

This invention relates to fastener-setting machines and more especially to machines for setting lacing-hooks. The majority of machines for setting lacing-hooks are provided with mechanism for feeding the work step by step to space the hooks, and it is with such machines that the present invention is more particularly concerned.

In a general sense an object of the invention is to improve the organization of such machines so as to insure greater accuracy, to minimize vibration and to increase the capacity for speed of operation.

More specifically an object is to control and operate the hook-engaging devices so as to insure accurate work at high speed. In this connection a feature of the invention consists in novel and improved means for coupling the hook-sustaining member and the clenching tool to a reciprocatory actuator in such manner that a single motion of the latter will retract the clenching tool and move the hook-sustaining member laterally to clear the throat of the clenched hook.

Another feature consists in organizing the aforesaid hook-sustaining member, clenching tool, and their common actuating mechanism in such manner that a single motion of the actuator will impart the final clenching motion and the throat-clearing motion.

When, as in the machine illustrated by the accompanying drawings, the hook-sustaining member has a carrying motion for transferring the hooks from a source of supply to the work such carrying motion is additional to but distinct from its throat-clearing motion. Former constructions designed to afford both these motions have been more or less deficient as to speed of operation, capacity to withstand the clenching stresses, or accuracy of registration with the source of supply and the clenching tool, because of mechanical difficulties which

are well known but which have not been solved heretofore as well as they might be. Accordingly an object of the invention is to improve the construction of this mechanism in hook-setting machines. A feature 60 of this part of the invention consists in a construction such that angular motions are wholly eliminated from the hook-sustaining member and from the members that engage it to impart the aforesaid carrying motion and clearing motion, and such that said motions are imparted by two members arranged to execute simple rectilinear motion transversely one to the other.

Other features of the invention are hereinafter described and claimed and are illustrated by the accompanying drawings.

Referring to the drawings, which illustrate a preferred embodiment of the invention,

Fig. 1 represents a front elevation of a hook-setting machine portions of which are broken out to show interior construction;

Fig. 2 represents an elevation, partly in section, of said machine as viewed from the right-hand side, the front of the machine being at the left of the figure;

Fig. 3 is a detail of mechanism represented in another position by broken lines in Fig. 2 and included also in Fig. 8;

Fig. 4 is a perspective view, partly in section, of the principal operating instrumentalities at the front of the machine;

Fig. 5 is a front elevation, partly in section, showing the work-engaging instrumentalities in their initial positions as when an article of work has been placed in operative position;

Fig. 6 is a view similar to Fig. 5 excepting that it shows the lower tool as having punched and fed the work, and the hook-carrier as having descended and about to insert a hook in the work;

Fig. 7, partly in elevation and partly in section in a plane from front to rear, shows the clenching tool in the act of completing the clenching of a hook, the hook-carrier and the hook-transferring member being about to move to the left and right respectively.

Fig. 8 is a perspective view, partly in section, including the hook-carrier, the hook-transferring member, mechanism for operating them in unison, and a portion of the plunger by which the hook-carrier is reciprocated toward and from the work;

Figs. 9, 10 and 11 represent top plan views including the delivery end of the raceway, the hook-carrier, the hook-transferring member, and a yielding member arranged to 5 copy the throat of the leading hook to support the latter before and during the transferring period;

Fig. 12 represents a front elevation of the leading hook at the delivery end of the raceway and includes broken lines representing portions of the raceway and means forming, conjointly therewith, a channel through which the neck of the hook is advanced by the transferring device, the direction and scope of this view being indicated by broken line 12-12 of Fig. 9;

Fig. 13 is a perspective view including the delivery end of the raceway, the hook-carrier and the yielding member for supporting 20 the leading hook in the path of the transferring member;

Fig. 14 shows another view of the elements included in Fig. 13; and

Fig. 15 is a sectional view through the structure intersected by broken line 15-15 of Fig. 2.

The general organization of the machine here represented is similar in some respects to that illustrated in my application Serial 30 No. 323,164, filed September 11, 1919. For example, the punching and feeding mechanisms are identical with those of the aforesaid application. Furthermore the construction of the presser-foot is similar in most respects to that shown in said application. The hopper for the lacing-hooks, and the mechanism for feeding the hooks out of the hopper are herein shown as embodying a construction similar in many respects to that 40 illustrated in United States Letters Patent 811,839 granted February 6, 1906 on my application. Accordingly the features of construction and operation that are common to this present case and to the aforesaid cases need not be so fully described herein as might otherwise be necessary since they are 45 sufficiently described in the earlier cases.

Before describing the details of construction it may be well to consider the general 50 organization of the machine. An article of work such as a shoe-quarter is placed right side up on a work-support and is held thereon by a presser-foot that bears down continuously while the work is being fed as well as while it is at rest. A punch-block is supported rigidly above the work but to all intents and purposes in contact therewith. The clenching tool is arranged below the work and is provided with a tubular pilot 55 that punches the work and then feeds the latter to hook-receiving position. The lacing-hooks are inserted into the work from above by a hook-carrier to which they are supplied one at a time. The hook is placed 60 on the carrier in such position that its head

is uppermost, the barrel portion of the hook extending downwardly from the carrier. When the hook-carrier descends the barrel of the hook encircles the pilot of the clenching tool and is ultimately clenched against 70 the under side of the work by the clenching surface at the base of the pilot. The clenching tool is then moved downwardly to withdraw it from the hook, and at the same time the hook-carrier is moved laterally to clear 75 the throat of the hook before it rises to receive another hook. The carrier then rises until it is in registration with the delivery end of the raceway, and while this is occurring the clenching tool moves to the right preparatory to punching another hole 80 in the work. While the hook-carrier is in its upper position it is moved to the rear until it is close to or actually touches the delivery end of the raceway, the hook-transferring device meanwhile advancing toward the hook-carrier to transfer the leading hook to the latter. This briefly describes the cycle 85 of the hook-setting instrumentalities.

An article of work such as that indicated 90 at 10 in Fig. 5 is laid on the work-support 11 and is held thereon by a presser-foot 12 that bears down continuously. The work-support is provided with a slot 13 through which the clenching tool 14 rises and along 95 which it moves to feed the work. This tool is carried by a plunger 15 that is reciprocated up and down by mechanism (see Fig. 2) including toggle members 16, a link 17, an operating lever 18 and a cam 19. This cam is affixed to a shaft 20 and moves the toggle members to the left from the initial position shown by Fig. 2 until the knee of the toggle has passed slightly beyond the 100 dead-center position. This motion causes the tubular pilot portion 21 of the tool to punch a hole through the work, the tool at that time being in registration with the punch-block 22 over the work, and the slight motion of the toggle beyond its dead-center 105 position relieving the punching pressure against the punch-block so that the tool 110 may be readily moved laterally to feed the work.

The punch-block is rigidly sustained by a 115 plunger 23, toggle members 24, 24, link 25, lever 26, stop screw 27 and abutment 28. A spring 29 attached to an arm of the lever 26 maintains the parts normally in the positions shown by Fig. 2 but permits the lever 120 to be moved by a treadle-rod 30 so as to lift the punch-block preparatory to presenting and removing an article of work.

The plunger 15 slides in a bearing afforded by a carriage 31, said carriage being arranged to slide horizontally on guide rods 125 32 for the purpose of feeding the work. The feeding motion is imparted to the carriage by an arm 33 affixed to a vertical rock-shaft 34. This rockshaft is oscillated with 130

a variable amplitude of motion by suitable mechanism including a cam 35 on the shaft 20. The carriage 31 is thereby reciprocated from the position shown by Fig. 5 to that 5 shown by Fig. 6 and vice versa. Whenever the feeding mechanism is adjusted to change the length of the feeding steps a corresponding change is made in the position of the punch-block so that the latter 10 will always stand in registration with the punching tool when the latter is executing its punching motion. For this purpose the plunger 23 that carries the punch-block is arranged to slide in an adjustable bearing 15 member 36, suitable connections including a lever 37 causing the bearing member to slide on a stationary supporting stud 38 whenever a change is made in the regulation 20 of the feeding mechanism. Mechanism embodying substantially the same construction as this is more fully described in my application Serial No. 323,164 above referred to.

The presser-foot 12 is also carried by the plunger 23 but is movable relatively to the 25 plunger so that it may maintain pressure on the work irrespective of the position at which the plunger is rigidly sustained. The presser-foot has sliding connection with the plunger and is engaged by a finger 39 30 formed on a member that includes a barrel 40 in which a compression spring 41 is enclosed. The member 39, 40 is connected to the plunger 23 by a pivot screw 42. A follower 43 projects through the lower end of 35 the barrel portion 40 so as to bear on an ear 44 of the plunger, the spring 41 being arranged to bear on the upper end of the follower and against a plug 45 in the upper 40 end of the barrel portion and thus to maintain downward pressure of the finger 39 on the presser-foot.

During the inserting and clenching operation a lacing-hook is sustained by a member comprising a head 46 and a stem 47. The 45 construction of this member is shown best by Fig. 8. Since, according to the illustrated embodiment of the invention, the hook-sustaining member, rather than the work, is moved to insert the lacing-hook, 50 said member is connected to and carried by a plunger 48. The lower end of this plunger is formed with grooves to receive, guide and brace flanges formed on the head 46, and is further provided with a trans- 55 verse hole 49 in which the stem 47 bears. The plunger 48 is reciprocated by a bell-crank lever having arms 50 and 51. These arms are arranged on a pivot stud 52 common to both and are rigidly but adjustably 60 connected to each other. The arm 51 is forked at its lower end so as to straddle a cam 53 carried by the shaft 20. Although the arm 50 is reciprocated positively the plunger 48 is capable of being arrested while said 65 arm continues to move upwardly, provision

being thus made for registering the hook-sustaining member with the raceway by which hooks are supplied to it. As shown by Figs. 1 and 4 the forward end of the arm 50 is forked and straddles a block 54. This block 70 is carried by a sleeve 55 through which the plunger 48 extends loosely. Downward movement of the sleeve is transmitted positively to the plunger by nuts 56 threaded on the plunger but upward movement of the 75 sleeve is transmitted by a compression spring 57 to a collar 58 affixed to the plunger. Referring to Fig. 2, an ear 59 projecting from the plunger 48 abuts against a set-screw 60 while the arm 50 is rising, the set-screw thus serving to arrest the plunger at any desired position before the arm has reached the upper limit of its motion. The head 46 of the hook-sustaining member may thus be registered relatively to the delivery 80 end of the raceway 61 as shown by Figs. 5 and 13. To facilitate the description of the hook-supplying mechanism it will be well 85 to designate the various parts of a lacing-hook so that the terms will be clearly understood. As indicated in Fig. 12, the lacing-hook comprises a barrel portion 62, shoulder 63, a neck 64 and head 65, the space between the shoulder and the head being hereinafter referred to as the "throat." 90

Referring to Figs. 9, 10 and 11 the lacing-hooks gravitate along the raceway from left to right, the hook-supporting strip 61 occupying the throats of the hooks, and a guard strip 66 being arranged to bear on 95 the barrel portions so as to keep the hooks on the supporting strip 61. As the hooks gravitate in the raceway they slide sidewise, their necks being guided by one edge of the strip 61. Although the raceway may have 100 any desired bends or twists between its receiving end and its delivery end the latter is substantially horizontal and stands so that the hooks are supported by their heads 105 as shown by Fig. 13.

The end-edge 67 of the raceway is substantially at right angles to the longitudinal edge on which the necks of the hook slide and is in registration with the hook-engaging flange of the hook-sustaining member. The leading hook in the raceway advances sidewise until it reaches the position indicated at 68 in Fig. 9, in which position its neck has passed beyond the corner formed by the edge 67 and the edge that leads the hooks thereto, although one side of its head overlaps said corner of the strip 61 (see Fig. 12). In this position the leading hook is in registration with a transferring member 69 by which it is subsequently transferred to the member 46. The hook is arrested in this position by a stationary abutment 70 which, in conjunction with the end or edge 67 of the raceway, forms a channel 74 through which the neck of the hook 110 115 120 125 130

passes as the hook is being transferred to the carrier 46. Although the hooks change direction at the aforesaid corner of the raceway strip they do not turn, but are prevented from turning and otherwise controlled by a yielding hook-supporting member 71 that initially constitutes an extension of the raceway and maintains the throat of the hook at the level of the hook-sustaining flange of the carrier 46. As shown by Figs. 9 and 15 the member 71 is in contact with the edge 67 of the raceway and is flush relatively to the upper and lower surfaces and the rear edge of the raceway so that the greater part of the head of the hook will slide along and be supported thereby after it has passed the edge 67. The supporting member 71 is mounted on a pivot member 72 and is normally held in hook-receiving position by a compression spring 73.

The channel 74 is slightly wider than the neck 64 of the hook but not so wide as the head of the hook. The transferring member 69 advances through the channel 74, thereby separating the leading hook from the next hook and causing the neck of the advancing hook to deflect the supporting member 71, which swings to the right and clears the neck entirely before the latter has passed out of the channel. While the hook is passing through the channel one side of its head continues to be supported by the delivery end of the raceway while, on the opposite side of the channel, the head of the hook slides from the member 71 to a lip 75 formed on the abutment 70. The movable member 71 constitutes a floating support by which the head of the hook is carried across the gap between the aforesaid corner of the strip 61 and the lip 75.

While the transferring member 69 is advancing to transfer the hook to the carrier 46 the latter moves in the opposite direction to receive the hook, the carrier finally reaching a position close to or in contact with the delivery end of the raceway and the lip 75 as shown by Fig. 11. When the hook is lodged on the carrier as shown by Figs. 11 and 7 its neck occupies a notch 76 formed in the carrier, and the hook is maintained with its neck in this notch while the carrier descends to insert and partially clench the barrel of the hook. As shown by Fig. 7 the hook-engaging portion 77 of the transferring member is elongated so as to maintain contact with the hook until the latter has been clenched. When the clenching operation has been partially effected by the complete downward movement of the hook-carrier it is completed by a slight upward movement of the clenching tool 14 due to return movement of the toggle members 16 to their dead-center line. Then, as the clenching tool descends, the hook-carrier moves horizontally to clear the hook, and at the

same time the transferring member is retracted in the opposite direction to enable the next hook to advance to the position indicated at 68 in Fig. 9. The plunger 48 is then raised to lift the hook-carrier to the level of the delivery end of the raceway and then the hook-carrier and the transferring member are again moved toward each other to deposit another hook on the carrier as hereinbefore explained.

The mechanism for operating the hook-carrier and the transferring member in unison is illustrated best by Fig. 8 and is shown also to some extent by Fig. 2. The stem 47 of the hook-carrier has flange-and-groove connection with a plunger 78 that is arranged to slide in fixed bearings 79, its lines of motion being transverse to those of the plunger 48. Flanges 80 formed on the stem 47 are inter-engaged with grooves 81 formed in a head carried by the forward end of the plunger 78, these formations serving to maintain operative connection between the plunger and the hook-carrier and enabling the latter to move up and down as aforesaid. A compression spring 82 acts against a collar 83 on the plunger 78 to move the hook-carrier to hook-receiving position, the movement of the hook-carrier in the opposite direction being effected by a lever 84 having a boss 85 arranged to act against the rear face of the collar 83. A set-screw 86 anchored in one of the bearing elements 79 is arranged to arrest the movement of the plunger 78 to the rear so as to prevent the spring 82 from pressing the hook-carrier too forcibly against the raceway. The transferring member 69 is arranged to be reciprocated in lines parallel to those of the plunger 78, and is actuated by an arm 87. A link 88 transmits motion from the lever 84 to the arm 87. This arm is arranged to swing on a pivot member 89 and its upper end is forked and arranged to straddle a block 90 carried by and pivotally connected to a block 91. The stem of the transferring member 69 extends loosely through a block 91, the block being confined between a collar 92 fixed to the stem and a compression spring 93. The spring is held under compression by nuts 94 on the stem. A washer 95 of soft material such as leather is interposed between the nuts and the bearing element 79 to limit the movement of the transferring member toward the hook-carrier. Although the block 91 is reciprocated positively in opposite directions its motion toward the left is transmitted to the transferring member 69 by the spring 93 so that the block may continue to move after the transferring member has been arrested, but the movement of the block in the opposite direction is transmitted positively to the transferring member by the collar 92. This reciprocating motion of the block 91 is trans-

mitted to the lever 84 by a stud portion 96 (Fig. 3) formed on or attached to the block. The stud portion 96 works in a slot 97 in the lever 84. This lever is mounted on a fulcrum member 98, and, when moving in a clockwise direction, continues after the plunger has been arrested. Consequently, during its first stages of motion in the opposite direction there is a period of lost motion 5 during which the clenching tool 14 completes the clenching operation as aforesaid. The connection between the transferring member 69 and the plunger 78 is such that, aside from said lost motion, these two elements 10 move in unison but in opposite directions, the movement of each being yielding in one direction and positive in the opposite direction. Moreover, since these elements are actuated and controlled by the lever 18 it 15 follows that the cam 19 not only produces the punching motion and the final clenching motion of the lower setting tool but also shifts the hook-carrier 46 relatively to the plunger 48 and also reciprocates the hook-transferring member 69.

Fig. 1 includes a disconnectible clutch for driving the cam shaft 20. Any suitable type of clutch may be provided for this purpose, the type illustrated being well known and 20 comprising a continuously rotating driving member 100 in the form of a pulley. The pulley is loosely mounted on the shaft and may be connected to and disconnected from the shaft at will by an axially movable bolt 101 25 under the control of a plunger 102. The bolt 101 is adapted to slide axially in a collar 103 affixed to the shaft and is provided with a head 104 having an inclined surface adapted to coact with the upper end of the plunger. 30 A compression spring 105 normally raises the plunger into the path of the head 104, but when the plunger is drawn down, as by a treadle rod 106, it releases the head 104, thus permitting the bolt 101 to establish 35 a driving connection under the influence of a spring (not shown) contained in the clutch. So long as the plunger 102 is held down the clutch will continue to drive the shaft but when it is raised by the spring 105 the clutch 40 is uncoupled in consequence of wedging action of the head 104 on the plunger.

It is hereinbefore stated that the arms 50 and 51 of the bell-crank lever that operates the hook-inserting plunger are adjustably 45 connected to each other. The features of construction shown by Fig. 15 provide for such relative adjustment and also provide for collective adjustment, one to correct inaccuracies of construction and the other to 50 vary the range of travel of the plunger according to whether the machine is to be used to operate on relatively thick or relatively thin work. The arm 51 has a hub 107 which bears on the fulcrum stud 52 and which is 55 turned down to receive the hub of the arm

50 so that the two hubs will occupy telescopic relation. The arms are rigidly connected by a clamping bolt 108 and an eccentric bushing 109 arranged thereon. The bushing occupies a slot 110 in the arm 51 60 and is clamped against the arm 50 by the bolt. When the bolt is loosened the arms may be relatively adjusted by turning the bushing, the latter having a head formed to receive a wrench for this purpose. Collective 65 adjustment of the arms to adapt the machine for thick or thin work is made possible by eccentricity of the fulcrum stud 52, the fulcrum portion being eccentric relatively to the end portions which bear in the 70 frame of the machine. A handle 112 is fastened to one end of the stud to afford convenient means for adjusting it. The handle is provided with an ear 113 which lies in contact with a flat face of the frame 75 and is pressed against the frame by a compression spring 114 so as to maintain friction sufficient to hold the fulcrum stud in any position to which it may be turned. The spring 114 is held under compression by 80 a stud 115 which extends through a concentric slot 116 in the ear and which is screwed or otherwise anchored in the frame 85 of the machine.

Having thus described my invention, what 90 I claim as new and desire to secure by Letters Patent of the United States is:

1. A hook-setting machine comprising a hook-carrier, and two operating members therefor arranged to execute simple rectilinear motion transversely one to the other, said carrier and each of said operating members having interengaged connecting portions by which the operating members maintain control of the carrier and by which 100 the latter is enabled to slide relatively to each of the operating members.

2. A hook-setting machine comprising two plungers arranged to execute simple rectilinear reciprocatory movement along lines 105 transverse to each other, and a hook-carrier having sliding flange-and-groove engagement with each of said plungers so as to be operated by, and movable relatively to, each of them.

3. A hook-setting machine comprising hook-setting mechanism including a hook-carrier, and two operating members therefor arranged and actuated to slide in fixed bearings along lines transverse to each other, said hook-carrier and each of said operating members having interengaged sliding connecting portions by which the hook-carrier is reciprocated relatively to the other operating member.

4. A hook-setting machine comprising hook-setting mechanism including a setting plunger, a hook-carrier carried thereby but movable relatively thereto transversely of 120 the plunger, and an operating member ar- 130

- ranged to reciprocate transversely of the plunger, the hook-carrier and said operating member having interengaged flange-and-groove portions by which they are operatively connected so that the hook-carrier may be reciprocated also by said plunger.
5. A hook-setting machine comprising hook-setting mechanism including a setting plunger, a hook-carrier carried thereby but movable relatively thereto transversely of the plunger, said hook-carrier having a shank bearing in and extending transversely through said plunger, one end of said shank having a flange, and an operating member arranged to reciprocate transversely of the plunger and having a groove in which said flange is arranged so as to slide co-incidently with movements of said plunger, said flange-and-groove being arranged to reciprocate the hook-carrier transversely of the plunger.
10. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
15. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
20. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
25. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
30. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
35. A hook-setting machine comprising hook-setting mechanism including a setting plunger having a hole extending transversely therethrough, a stem arranged to bear in said hole so as to slide transversely of the plunger, said stem having a head at one end constructed and arranged to carry a lacing-hook and having a flange at the other end, and an operating member arranged to reciprocate transversely of said plunger and having a groove in which said flange is arranged to transmit the reciprocation of said operating member to said stem and to slide coincidentally with the movements of said plunger.
40. A hook-setting machine comprising setting mechanism including a punching tool and a movable hook-sustaining member, a raceway for supplying lacing-hooks to said member, a movable member arranged to transfer the leading hook from the raceway to said hook-sustaining member, mechanism including a reciprocatory member arranged to impart punching movement to said punching tool, and means operable by said reciprocatory member and arranged to move said hook-sustaining member and said transferring member in unison.
45. A hook-setting machine comprising a clenching tool and a movable hook-sustaining member, mechanism including a reciprocatory member arranged to move said clenching tool axially, means operable by said reciprocatory member to retract said hook-sustaining member out of the clenched hook, and means to hold the work stationary while said hook-sustaining member is being retracted as aforesaid.
50. A hook-setting machine comprising a clenching tool and a movable hook-sustaining member, mechanism including a reciprocatory member arranged to move said clenching tool axially, means operable by said reciprocatory member to retract said hook-sustaining member out of the clenched hook, and means to hold the work stationary while said hook-sustaining member is being retracted as aforesaid.
55. A hook-setting machine comprising a clenching tool and a movable hook-sustaining member, mechanism including a reciprocatory member arranged to move said clenching tool axially, means operable by said reciprocatory member to retract said hook-sustaining member out of the clenched hook, and means to hold the work stationary while said hook-sustaining member is being retracted as aforesaid.
60. A hook-setting machine comprising a hook-sustaining member, a clenching tool, mechanism for moving said hook-sustaining member toward and from said clenching tool, mechanism including a reciprocatory element for moving said clenching tool to-

ward and from said hook-sustaining member, and connections operable by said reciprocatory element for moving said hook-sustaining member laterally.

10. A hook-setting machine comprising a clenching member and a hook-sustaining member arranged to cooperate, toggle mechanism arranged to move one of said members toward and from the other, a reciprocatory member arranged to operate said toggle mechanism, means operable by said reciprocatory member to move said hook-sustaining member so as to clear the clenched hook, and means to hold the work stationary while said hook-sustaining member is moving as last specified.

11. A hook-setting machine comprising a punching tool, mechanism including a reciprocatory member for operating said tool, a hook-sustaining member, hook-supplying means, a member arranged to transfer a hook from said supplying means to said hook-sustaining member, and means arranged to transmit motion from said reciprocatory member to operate said transferring member.

12. A hook-setting machine comprising a clenching tool, a hook-carrier arranged to cooperate therewith, means arranged to move said hook-carrier toward the clenching tool to insert the barrel of a fastener, mechanism including a reciprocatory member for moving the clenching tool toward said hook-carrier to clench the hook and then away from the hook-carrier to clear the clenched portion of the hook, and means operable by said reciprocatory member to shift the hook-carrier laterally as the clenching tool moves away from the hook-carrier as aforesaid.

13. A hook-setting machine comprising a clenching tool, a hook-carrier arranged to cooperate therewith, means arranged to move said hook-carrier toward the clenching tool to insert the barrel of a fastener, toggle members arranged to reciprocate said clenching tool, mechanism including a reciprocatory member for moving the knee-joint of said toggle members across the dead-center position, and means operable by said reciprocatory member to shift said hook-carrier laterally as said knee-joint moves away from said dead-center position.

14. A hook-setting machine comprising a clenching tool, a hook-carrier arranged to cooperate therewith, means arranged to move said hook-carrier toward the clenching tool to insert the barrel of a fastener, an operating lever, mechanism operable by said lever to operate said clenching tool and including toggle members the knee-joint of which is movable across the dead-center position to clench the hook and then retract the clenching tool, and means also operable by said lever to shift said hook-carrier laterally

- as said knee-joint moves away from said dead-center position.
15. A hook-setting machine comprising a movable member for sustaining the hook 5 while it is being set, mechanism including a reciprocatory operating member arranged to shift the movable member laterally so as to clear the clenched hook, and means also operable by said operating member to impart 10 clenching movement and retractive movement to the clenching tool as the said operating member moves in one direction and to complete such clenching movement prior to the shifting of said hook-carrier as aforesaid.
16. A hook-setting machine comprising a hook-sustaining member, a clenching tool movable toward and from said member, an operating lever, mechanism operable by 20 said lever to impart clenching movement to said tool, mechanism also operable by said lever to shift said member transversely of the lines of clenching movement, and mechanism arranged to move said clenching tool 25 to feed the work.
17. A hook-setting machine comprising a hook-sustaining member, a clenching tool movable toward and from said member, an operating lever, mechanism operable by said 30 lever during the latter stages of its movement in one direction to shift said member so as to clear the clenched hook, said mechanism providing for lost motion during the first stages of said movement, and mechanism operable by said lever during said first 35 stages to impart clenching movement to said tool and operable during said latter stages to retract the clenching tool from the clenched hook.
- 40 18. A hook-setting machine comprising a hook-sustaining member movable laterally to clear the throat of the clenched hook, a clenching tool movable toward and from said hook-sustaining member, and operating mechanism including a reciprocatory member and connections from the latter to said tool and hook-sustaining member, respectively, such that movement of said reciprocatory member in one direction imparts 45 clenching movement and throat-clearing movement to said tool and hook-sustaining member respectively.
- 50 19. A hook-setting machine comprising a hook-sustaining member and a clenching member one of which is movable toward and from the other, the first of said members being movable laterally to clear the throat of the clenched hook, and operating mechanism including a reciprocatory actuator 55 and connections therefrom to said members, respectively, such that movement of said actuator in one direction imparts clenching motion to one of said members and throat-clearing motion to said hook-sustaining member.
- 60 20. A fastener-setting machine comprising a reciprocatory tool, an actuator therefor, and a two-armed lever arranged to transmit motion from said actuator to said tool, the arms of said lever being relatively adjustable angularly about an axis and having lapped portions adjustably connected by a rotatively adjustable eccentric member and means for maintaining said member in various positions of adjustment. 70
- 75 21. A fastener-setting machine comprising a reciprocatory tool, an actuator therefor, and a two-armed lever arranged to transmit motion from said actuator to said tool, the arms of said lever having telescopically related hub portions and lapped connecting portions, and adjusting means connecting said lapped portions so as to maintain said hub portions in telescopic relation and vary the angular relation of said arms. 80
- 85 22. A hook-setting machine comprising a hook-sustaining member, a clenching tool movable toward and from said member, the latter being movable transversely of the lines of clenching pressure, mechanism including a reciprocatory member for moving said tool toward and from said hook-sustaining member, and operating means arranged to transmit motion from said reciprocatory member to move said hook-sustaining member out of the clenched hook. 90
- 95 23. A hook-setting machine comprising hook-supplying means, a hook-sustaining member movable to and from hook-receiving position relatively to said means, a punch, mechanism including a reciprocatory member for operating said punch, and means operable by said member for moving said hook-sustaining member to said 100 hook-receiving position.
- 105 24. A hook-setting machine comprising a hook-sustaining member, a hook-supplying means including a feeder arranged to transfer a hook to said hook-sustaining member, punching mechanism including a reciprocatory member, and means operable by said reciprocatory member to operate said feeder. 110
- 115 25. A hook-setting machine comprising a hook-sustaining member and a hook-feeder movable toward each other, the one to receive and the other to supply a lacing hook, punching mechanism, and means operable by said punching mechanism to move said hook-sustaining member and said feeder as aforesaid. 120
- 125 26. A hook-setting machine comprising a hook-sustaining member, punching mechanism, and means operable by said punching mechanism to supply a lacing hook to said member.
- 130 27. A hook-setting machine comprising a hook-sustaining member and a clenching tool arranged to cooperate, mechanism for

moving said hook-sustaining member to insert and clench a lacing hook, mechanism for reciprocating said clenching tool, and means operable by the latter said mechanism to move said hook-sustaining member out of the clenched hook.

28. A hook-setting machine comprising a hook-sustaining member and a clenching tool arranged to clench a lacing hook, mech-

anism arranged to reciprocate said tool, and means operable by said mechanism to supply a lacing hook to said hook-sustaining member and thereafter to move said member out of the clenched hook.

In testimony whereof I have signed my name to this specification.

PERLEY R. GLASS.
